GARMENT FORMER

Clarence E. Journey, Elkton, Fla.

Application October 10, 1949, Serial No. 120,456

6 Claims. (Cl. 223—72)

The present invention relates to garment formers for use with pressing machines, and more particularly has reference to a former for shaping a sleeve and at least a portion of the shoulder.

It is, of course, common practice after a garment has been cleaned to expand or stretch the wrinkled sleeve and then subject the sleeve to hot steam to soften the wrinkles. This is accomplished by placing the sleeve over a form where it is maintained under a slight amount of tension, after which the sleeve is cooled or dried while still on the form. Numerous sleeve formers of different types are currently on the market, but these formers are not entirely satisfactory as far as the dry cleaning field is concerned. One objection to the formers is the fact that they are rather flimsy in structural detail, and, as a consequence, the stretcher members frequently break within a short period of use. Another disadvantageous feature is that the operating handle and its associated locking parts are complex both as to structure and operation, thereby making the former difficult to manipulate with the attendant increase in the time cycle for pressing process. Perhaps the main failing of the formers is that they cannot be employed for all types of sleeves and are not capable of shaping the shoulder.

An important object of my invention is to provide a sleeve former which will overcome the above and other objectionable features now present in the field.

Another object of the invention is to provide a former by the use of which short, three-quarter or full length sleeves may be properly shaped.

Yet a further object is to provide a sleeve former wherein the relatively stationary member is provided with an angular offset which follows approximately the shoulder contour, thereby enabling at least a portion of the shoulder to be shaped simultaneously with the sleeve.

A further object of the invention is to provide a garment former wherein one of a plurality of various shoulder lifting attachments may be detachably connected to the stationary member for correctly shaping the particular sleeve being pressed.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which:

Figure 1 is an elevational view showing the former in operative position with one of the lifting attachments in position.

Figure 2 is a vertical sectional view of the former.

Figure 3 is a bottom view of the former.

Figures 4 and 5 are views taken along the lines 4—4 and 5—5 of Figure 2, looking in the direction of the arrows.

Figure 6 is a perspective view of one of the lifting attachments.

Figure 7 is a view taken along the line 7—7 of Figure 6, looking in the direction of the arrows.

Figure 8 is a perspective view of another lifting attachment, primarily for use with ladies' sleeves.

Figure 9 is a perspective view of another shoulder lifting attachment, finding particular use with men's coat sleeves.

Figure 10 is a view taken along the line 10—10 of Figure 9, looking in the direction of the arrows.

2

Figure 11 is a front elevational view, partly broken away, of an adjustable lifting attachment.

Figure 12 is a vertical sectional view of the attachment shown in Figure 11.

Figures 13 and 14 are front elevational views of the movable and fixed elements of the attachment shown in Figure 11.

Figure 15 is an elevational view showing the former used with a short sleeve of the type not having a shoulder puff.

Figure 16 is a view similar to Figure 15 showing the former used with a sleeve having a puff.

As shown in Figure 2, the sleeve former comprises a substantially fixed or immovable element 10 and a movable element 11 pivotally connected to the element 10, as indicated generally at 12. Each of the elements 10 and 11 is ovoid or egg-shaped in cross section and is made of Florida Cedar and the elements are sanded to provide smooth external surfaces, thus preventing any danger of the former hanging or catching in the sleeve lining.

The element 10 is formed with an angular offset 13 at one end thereof, the offset being at an angle which follows the line extending from the neck to the shoulder, and the offset 13 and element 10 are preferably separate pieces which are joined together as shown at 15. To form the joint 15, the element 10 is provided with an arcuate groove or channel 16, and groove 17 on the same radius is formed in the offset 13. A circular disk 18 preferably of a laminated type is inserted and adhesively secured in the grooves 16 and 17, thus forming a very strong joint at the juncture of the offset and the fixed element.

The pivotal connection 12 includes a steel rod 19 of the necessary resiliency, and one end of the rod is bent to form an eye 20. The eye 20 is lodged in a longitudinal recess 21 in the inner face of the movable element 11 and is secured therein by means of a transversely extending pin 22. The rod is also offset as at 23 and is shaped to form a U leg 24. A handle or grip portion 25 is conveniently attached to the free end of the rod for the customary purpose. The lower face of both the offset 13 and the element are grooved longitudinally as indicated at 26, and a pin or roller 27 attached to the element 10 engages the base of leg 24 so that the rod may be hingedly secured to the element 10. It is advisable that a fabric or similar sheath 28 be applied to the rod 19.

When the elements 10 and 11 are in the inoperative position, the rod will be nested in the recess 21 and the groove 26, thus affording a highly compact unit which requires a minimum of space for storage or transportation.

Furthermore, the rod offset 23 by virtue of its seat in the groove 26 will prevent any lateral displacement of the element 11 relative to the element 10.

In order that the handle 25 will be properly secured to the end of the rod 19, it can be seen that the rod is fitted into a bore formed in the handle, and an annular groove 30 extends around the handle 25 adjacent each end thereof. A cord or the like 31 is seated in each groove 30 to strengthen the handle and prevent its fracture. In order to lock the handle and, as a consequence, the position of the element 11 with respect to the element 10, it will be noted that a heavy duty ball chain 32 is anchored at one end to the handle as indicated at 33. The offset end of the chain 32 extends through a metal loop 34 having a narrow slot 35 and a ring 36 of such diameter as to permit the chain to be readily drawn therethrough. The free end of the chain carries an enlargement 37 which will prevent the chain from being completely withdrawn from the ring 36. In view of the fact that the metal loop 34 is subjected to considerable strain, the loop is anchored in a wooden block 38 which is inserted in a recess in the end of the offset 13 and the grain of the block 38 is at right angles to that of the offset to reduce to a minimum any danger of breakage. Manifestly, by pulling the chain through the ring 36 and thereafter moving the chain into the narrow portion 35, the handle will be locked in that particular position. The locking can be very easily and quickly accomplished and the unit may be unlocked by again moving the chain into the ring 36.

The free end of the element 10 is recessed as shown at 40 and one end of a spring 41 is anchored therein, as shown at 42. The opposite end of the spring is attached to a pin or the like 43 which is seated in a longitudinal groove 44 adjacent the nose end of the element 11, and the spring 41 tends to draw the noses of the elements 10 and 11 together. Consequently, the opposite or tail end of the element 11 is urged away from the element 10, and this arrangement is particularly efficacious, in that it will enable the former to be employed with both short and three-quarter length sleeves, which heretofore has not been possible with the formers currently on the market.

The element 10 adjacent its point of junction with the offset 13 is formed with a transversely extending depression or indentation 45 which is located substantially at the seam line of the sleeve and this indentation will enable a padded shoulder to fit therein so that full tension may be exerted inside the sleeve up to the seam where the sleeve joins the shoulder without bulging the shoulder, as indicated in Figure 2 by the broken line.

In using the former with a man's coat sleeve, the chain is supported in the unlocked position which, of course, will enable the elements 10 and 11 to be in their nested position and the nose of the former is then inserted into the sleeve and the seam is lodged in the indentation 45. The handle 25 is then moved toward the offset 13 which, of course, will swing the element 11 away from the element 10, thus expanding or stretching the sleeve. The chain 32 is then locked to hold the parts in the adjusted position. The sleeve may then be drawn forwardly along the former and thus smoothing the wrinkles in the sleeve, and by virtue of the spring 41, tension will be imparted at the arm pit by the tail end of the element 11. Inasmuch as the offset 13 follows the shoulder line, the shoulder of the coat, or at least a portion thereof, will be stretched, which heretofore could not be achieved with the conventional formers.

As previously indicated, it has been difficult, if not impossible, to use formers with short or three-quarter length sleeves. However, with the present invention this is overcome and, as shown in Figure 15, a short sleeve may be perfectly stretched by virtue of the spring 41 which will keep the under portion of the sleeve under tension that will effectively remove the wrinkles.

As previously mentioned, an important feature of the invention is to provide means whereby shoulder lifting attachments may be connected to the former, and to accomplish this end, it will be noted in Figures 2 and 4 that the offset 13 is provided with a plurality of spaced through-extending apertures 47, each of which is lined with a metal sleeve or the like 48. While I have shown the use of three such apertures, it is, of course, obvious that a more or less number may be employed, but experience has shown that with the majority of sleeves, three apertures are sufficient. A shoulder lifting attachment is adapted to be employed with the apertures, and in Figures 6, 8, 9 and 11 there are shown four types of attachments which should take care of any type of problem encountered. In Figure 7 there is shown a supporting strap 50 of metal or the like having a pin 51 adjacent one end thereof, the pin 51 being adapted to be inserted in the desired aperture 47. An egg-shaped or oval body 52 is formed with a recess 53, in which is anchored a helical spring 54. The spring 54 is welded or otherwise secured to the free end of the strap 50 and consequently, the body 52 may have a free swiveling movement on the strap. This particular type of attachment may be employed for small sleeves such as children's sleeves. The form illustrated in Figure 8 is primarily employed for women's sleeves, and body 60 is of arcuate configuration and the upper free edge is curved from front to rear, as shown at 61. The body 60 is, of course, pivotally carried by strap 62 such as by means of a machine screw or the like.

The unit shown in Figures 9 and 10 includes a body 70, generally similar in outline to that of Figure 8, although the upper edge is approximately pointed, as shown at 71, and this body is employed for lifting men's sleeves at the seam line. Herein again the body 70 is rotatably attached to the supporting strap 72, as indicated at 73.

The attachment shown in Figure 12 is of an adjustable nature to take care of extremely high shoulders. The

unit comprises a triangular base 80 which is swiveled to a supporting strap 81 by means of a machine screw 82. An operating handle 83 is anchored to the base 80, as indicated generally at 84, and the handle 83 is of slightly greater length than strap 81 in order that the operator's hands will be distantly removed from the press to enable the base to be turned about the screw 82. The angular face of the base 80 is formed with a plurality of spaced apertures 85, and a pair of elongated slots 86 are located on opposite sides of the apertures 85. A complementary block 87 is adapted to rest on the angular face of the base 80, and a pin 88 extends from the lower face of the block. Manifestly, by locating the pin 88 in the desired aperture 85, the position of the block relative to the base may be readily adjusted. To prevent swiveling movement of the block 87, the block also supports a pair of pins 89 which are so disposed as to enter the elongated slots 86, as clearly indicated in Figures 13 and 14. For an unusually high sleeve, the pin 88 would be inserted in the uppermost aperture 85, while for a normal height sleeve the pin would be lodged in the lowermost aperture.

To illustrate the use of the lifting attachments, attention is called to Figure 1 wherein after the sleeve has been stretched by moving the element 11 away from the element 10 and the parts locked in that position, the pin of the attachment strap (attachment shown in Figure 9) is disposed in the proper aperture 47 and the strap swung inwardly until the body 70 follows the seam line of the sleeve, whereby the edge 71 will engage the seam and elevate the upper end of the sleeve above the former, as clearly indicated in Figure 1. By pulling the sleeve toward the nose end, the wrinkles will be removed and a smooth even line will extend from the seam to the cuff. To remove the attachment, it is merely swung toward the handle 25 and the pin withdrawn from the recess or aperture 47. To use the attachment for the opposite sleeve, the former is merely reversed and the same cycle of steps repeated. This is particularly important, in that the arrangement may be readily employed for both the right and left sleeves. It is thought that the above description should suffice to illustrate the mode of operation of the lifting attachments, although in Figure 16 I have shown the attachment used with a lady's short sleeve having a puffed shoulder, in which situation the body such as that shown in Figure 8 would be employed. The spring 41 will keep the sleeve fully extended at the arm pit and the body 60 will lift the shoulder so that a smooth line is presented for at least a portion of the shoulder portion of the garment, the puff and the sleeve body.

I claim:

1. In a former for garments having a shoulder portion and a sleeve secured to the shoulder portion, a substantially immovable member, a movable member, said immovable and movable members being disposed in side by side relationship, means pivotally connecting said immovable and movable members whereby the movable member can be moved toward and away from the immovable member, resilient means interconnecting said members adjacent one end of said members, an offset extending at an obtuse angle from one end of said immovable member, the angle of the offset being approximately that of the shoulder line, a handle carried by the pivotal connection between the immovable and movable members in proximity to the offset, whereby movement of the handle toward the offset moves said movable member away from the immovable member, and complementary means carried by the handle and the offset to lock the members in their adjusted position.

2. A sleeve former as claimed in claim 1 wherein said offset is provided with a recess at the juncture of the offset with the immovable members, the offset being adapted to receive the seam between the sleeve and the shoulder portion.

3. In a former for garments having a shoulder portion and a sleeve secured to the shoulder portion, a pair of rigid complementary members positioned in side by side relationship, one of said members being provided with an angular offset at one end thereof, said offset extending at an obtuse angle to said member and substantially following the line of the shoulder portion, means pivotally interconnecting the members for movement toward and away from each other, a shoulder lifting body, complementary means on the shoulder lifting body and offset defining a pivotal connection between the shoulder lifting body whereby said offset may be moved to a position

below the seam between the sleeve and the shoulder portion to elevate the sleeve at the seam.

4. A shoulder lifting attachment for use with a former for garments having a shoulder portion and a sleeve secured to the shoulder portion comprising a support element, a connection between the support element and the former, a base swiveled to the support element and having an inclined wall, a lift member adapted to be disposed on said inclined wall, and complementary means on the inclined wall of said base and on said lift member to secure said member at different positions on the inclined wall of the base.

5. In a former for garments having a shoulder portion and a sleeve secured to the shoulder portion, a substantially immovable member, a movable member, said immovable and movable members being disposed in side by side relationship, means pivotally interconnecting the said immovable and movable members whereby the movable member can be moved toward and away from the immovable member, an offset extending at an obtuse angle from one end of said immovable member, the angle of the offset being approximately that of the line of the shoulder, a handle carried by the pivotal interconnection between the immovable and movable members so that movement of the handle toward the offset moves the movable member away from the immovable member.

15

10

20

25

6. In a former for garments having a shoulder portion and a sleeve secured to the shoulder portion, a pair of rigid complementary members disposed in side by side relationship, a pivotal connection between said members whereby said members may have movement toward and away from each other, an offset on one of said members arranged at an obtuse angle to said member, and the angular offset substantially following the line of the shoulder portion, the angular offset being formed with an indentation at its juncture with said member to permit the seam between the sleeve and the shoulder portion to fit therein.
